UNITED STATES PATENT OFFICE

FRANK G. MARCIANO, OF PROVIDENCE, RHODE ISLAND, ASSIGNOR TO UNIVERSAL OPTICAL CORPORATION, OF PROVIDENCE, RHODE ISLAND, A CORPORATION OF RHODE ISLAND

DESIGN FOR AN EYEGLASS FRAME

Application filed October 18, 1929. Serial No. 33,087. Term of patent 14 years.

To all whom it may concern:

Be it known that FRANK G. MARCIANO, a citizen of the United States of America, residing at Providence, in the county of Providence and State of Rhode Island, has invented a certain new, original, and ornamental Design for an Eyeglass Frame, of which the following is a specification, reference being had to the accompanying drawings, forming a part thereof.

Fig. 1 is a front elevation of an eye glass frame showing my new design.

Fig. 2 is a plan view of the same.

I claim:

The ornamental design for an eye glass frame substantially as shown.

In testimony whereof I affix my signature.

FRANK G. MARCIANO.
